SUPPORTING BLOCK FOR WHEELS

Emil Veselik, Flossmoor, Ill., and Marion C. Wilson,
Dyer, Ind., assignors to Calumet Steel Castings Corporation,
Hammond, Ind., a corporation of Indiana

Filed Mar. 8, 1965, Ser. No. 84,134

Term of patent 14 years

(Cl. D41—1)

FIG. 1

FIG. 2

FIG. 3

FIG. 4

FIGURE 1 is a perspective view of a supporting block for wheels showing our new design and in which one end, top and one side of the block are visible;

FIGURE 2 is an elevational view of the side opposite that visible in FIGURE 1;

FIGURE 3 is an elevational view of the end opposite that visible in FIGURE 1; and

FIGURE 4 is a bottom plan view thereof.

We claim:

The ornamental design for a supporting block for wheels, substantially as shown and described.
